UNITED STATES PATENT OFFICE.

JOSEPH H. SCHNEIDER, OF DRIFTING, PENNSYLVANIA.

DESIGN FOR A SPOKE-THIMBLE.

SPECIFICATION forming part of Design No. 27,139, dated June 1, 1897.

Application filed April 6, 1897. Serial No. 631,033. Term of patent 14 years.

To all whom it may concern:-

Be it known that I, JOSEPH H. SCHNEIDER, a citizen of the United States, residing at Drifting, in the county of Clearfield and State of Pennsylvania, have invented and produced a new and original Design for a Spoke-Thimble for Repairing Wheels; and I do hereby declare the following to be a full, clear, and exact description of the same, reference being had to the accompanying drawing, forming a part thereof.

My invention relates to a design for spoke-thimbles for repairing the spokes of vehicle-wheels where the tenon has broken off in the felly.

My invention relates to the entire configuration of the thimble, and especially to the thimble illustrated in the accompanying drawing, in which the figure is a perspective view of a spoke-thimble embodying my design.

The leading features of my design appear in the following description.

1 represents the spoke-thimble, and it is formed with a cylindrical socket 2 and its 25 closed end with two longitudinal alined ears 3 3, each of which is formed with a countersunk orifice 4. The edges of the ears 3 3 are formed with semicircular recesses and terminate in converging ends, as shown. 30

Having thus fully described my invention, what I claim as new and useful, and desire to secure by Letters Patent of the United States, is—

The design for a spoke-thimble, substantially as shown and described. 35

In testimony whereof I affix my signature in presence of two witnesses.

JOSEPH H. SCHNEIDER.
